UNITED STATES PATENT OFFICE.

EDWIN A. WEBSTER, OF GROVELAND, MASSACHUSETTS, ASSIGNOR, BY MESNE ASSIGNMENTS, TO HAMEL SHOE MACHINERY COMPANY, OF LYNN, MASSACHUSETTS, A CORPORATION OF MASSACHUSETTS.

LIP-TURNER.

1,219,792.

Specification of Letters Patent. Patented Mar. 20, 1917.

Application filed October 7, 1912. Serial No. 724,238.

To all whom it may concern:

Be it known that I, EDWIN A. WEBSTER, a citizen of the United States, residing at Groveland, in the county of Essex and State 5 of Massachusetts, have invented an Improvement in Lip-Turners, of which the following is a specification.

This invention relates to that class of machines known as lip-turning machines, 10 which are especially adapted to raise the lip at the edge of a welt inner sole, which has been channeled, and then bend it over and lay it flat on the inner surface of the shoe.

15 Prior to my invention various devices have been produced for raising the lip and setting it in a predetermined position, one of which comprises a reciprocating hammer which is arranged to strike the lip at its base and upset it, so that it will be held in a vertical or slightly bent-over position. This method is objectionable for the reason that, as the blow of the hammer is directed at the base of the lip, it frequently tears the lip 20 from the sole or weakens the portion of the leather which connects it to the sole and places an objectionable strain thereon.

25 In another type of machine more nearly similar to the machine which constituted the subject-matter of my invention, in which the purpose is not only to raise the lip, but to bend it back and lay it flat on the surface of the sole, a hammer is provided with means for causing it to strike a vertical blow on the lip after it has been raised by the plow and bent back to or beyond the vertical position. With this type of machine the lip 30 is frequently struck directly on its edge, while in a vertical position, causing it to be beaten down without being bent over. This is especially liable to occur when the lip is short and thick.

Difficulty has also frequently been encountered in setting the lip in bent-over position 40 when it is short and thick, as it tends strongly to return to its natural position.

The object of my invention is to provide a machine of the above character which is adapted to raise the lip and then turn it over 45 and down onto the surface of the sole, so that it will be set in this position without liability of having the lip-setting means beat down the lip without having it turned over.

A further object is to provide a machine

which shall be of simple and durable construction, so that it is unlikely to get out of order, and may be manufactured at small expense.

I accomplish these objects by the means shown in the accompanying drawing, in which,

Figure 1 is a side elevation of a machine made according to my invention.

Fig. 2 is a plan view thereof, and

Figs. 3 and 4 are detail views illustrating the manner of turning over and setting the lip.

Figs. 5 and 6 are detail sectional views of the hammer and its holder.

In the drawing 1 indicates the base of the machine having a bracket 2 thereon in which the main shaft 3, which is driven from a suitable source of power, is mounted. Said shaft has an eccentric 4 thereon on which a block 5 is mounted, said block being arranged to slide between the arms of a lever 6 which is mounted to oscillate on a shaft 7 in a bracket 2, so that as said shaft 3 is driven said lever will be oscillated.

The shaft 3 is also provided with a worm 80 9 which is arranged to engage a worm gear 10 mounted on an inclined shaft 11, said shaft being journaled in the base of the machine and also in a bracket 12, secured to the front side thereof. A feed wheel 13 is 85 mounted on the upper end of said shaft, said feed wheel being adapted to bear on the edge portion of the sole from which the lip has been cut. A vertically yielding shaft 14 is mounted to rotate vertically in the 90 bracket 12, and is provided with a circular feed table 15 on the upper end thereof, and suitable treadle mechanism, not shown, for drawing down the table is provided. A gear 16 is mounted on the shaft 11 and arranged 95 in mesh with the gear 17 on the shaft 14, so that the sole-engaging portions of the feed wheel and table are driven at the same surface speed.

According to my invention I provide an 100 arm 18 which is mounted on pivot 19 adjacent the base of the machine, at a considerable distance beneath the level of table 15, and also some distance in the rear thereof, and extends upwardly from said pivot 105 to points above the level of the table. Said arm 18 is provided with a socket 18' which extends at right angles therefrom at its up-

per end, and a depending hammer holder 20 is adjustably mounted in said socket and is adapted to be secured therein by a clamping screw 21.

5 A hammer 22, which is square in cross-section, is reciprocally mounted in a correspondingly shaped recess in said holder 20, in a position nearly parallel to the arm 18 and a screw 220 extends through said holder 10 and is threaded in the upper end of the hammer, the head of said screw normally resting on the upper end of the holder. A spring finger 23 is secured on the lever 18 and rests on the head of the screw 220 and normally holds the same against the holder.

15 The lower end of the hammer 22 is provided with an engaging face 22', which is obliquely inclined with relation thereto, as shown in Figs. 3, 4 and 5. A link 24 is connected to the upper end of the arm 6 and to the upper end of the arm 18, so that as the shaft 3 is rotated, said arm 18 will be oscillated.

20 A plow 25 is mounted on brackets at one side of the hammer 22, in position to pass between the surface of the sole and the lip, so as to raise it in the usual manner.

25 A lip depressing finger 26 is also rigidly secured on bracket 27 at the opposite side 30 of the hammer 22 and in position to bear on the lip, after it has been turned over, as hereinafter described.

35 In operation, the table is rotated in the direction of the arrow in Fig. 2, and the sole is passed between the table and the feed-wheel 13 in the usual manner.

40 The arm 18 is oscillated, and, as the center about which it swings is located at a considerable distance below the level of the table 15, and in the rear thereof, the hammer 22, which is held so that it depends directly over the edge portion of the table in a nearly vertical position with relation thereto, will be carried laterally, or in a direction transversely thereof, and with its face nearly parallel to the surface of the table, and, at the same time also longitudinally downward toward the table. The path of movement of the hammer is such that its 45 face 22' either is caused to engage the edge of the lip which has previously been raised by the plow, or its front side is caused to engage the side of the lip closely adjacent its edge and to bend it over and press it, or hammer it down, so that it lies flat on the inner surface of the sole, as shown in Figs. 3 and 4. That is, the hammer strikes down on the lip with what may be termed a "drawing blow". The face 22' of the hammer 50 is made slightly oblique to the sides thereof, so that said face will be held flat with the sole at the end of its strike, and will also have a drawing or pushing effect until it reaches that point. As the hammer 55 is adapted to yield upward, slightly, against

the action of the spring 23, and as the table 15 is also adapted to yield downwardly, variations in thickness of soles and of the lip are provided for.

60 Whether the hammer first strikes directly 70 on the upturned edge of the lip with its face 22', or whether its side first strikes the under side of the lip and then pushes it over, so that the lip is then engaged by its face 22', depends on whether the lip is short or long, and on the vertical adjustment of the hammer by screw 220.

65 While the hammer will press the lip down from the vertical position of Fig. 3 to the position of Fig. 4, the lip will not always be 80 fully set in this position, and for this reason I preferably provide the finger 26 which bears firmly on the lip after it is turned down, and as the sole is fed beneath it, and materially assists in setting the lip in the 85 turned down position.

75 While the above described construction is a preferable form of my invention, various other forms of mechanism may be produced which will cause the combined downward 90 and forward movement of the hammer, above described to take place.

I claim:—

1. A lip-turning machine comprising a sole support, a plow for raising the lip, a 95 hammer having a face at its end, and means to hold said hammer with its face approximately parallel to the face of said support and to cause simultaneous transverse and longitudinal movements thereof, so that its 100 said face is carried over and toward the surface of the sole supported thereon, to bend back the lip and beat it down toward the sole.

2. A lip-turning machine comprising a 105 table having a sole-supporting surface, a plow for raising the lip, an arm pivotally mounted below the level of said surface and having means to oscillate the same, and a hammer arranged to be carried laterally by 110 said arm and having a lip-engaging face at its end arranged to be moved to and from said surface as said arm is oscillated and to be held in angular positions which vary from an oblique position, at the beginning 115 of its operative movement, to a position approximately parallel to said surface at the end of said movement.

3. A lip-turning machine comprising a sole support, a plow for raising the lip, an 120 arm pivotally mounted beneath said support and at one side thereof, said arm extending upwardly therefrom, a holder projecting forwardly from said arm over said support, and having a hammer at the end 125 thereof provided with a downwardly facing lip-engaging face, and means to oscillate said arm to carry the face of the hammer over and toward said support.

4. A lip-turning machine comprising a 130

sole support, a plow for raising the lip, an arm pivotally mounted beneath said support and at one side thereof, said arm extending upwardly therefrom, and a hammer 5 held by said arm over said support and movable therewith toward and from the same, said hammer having an oblique face at its under side arranged to be carried into a position of approximately parallelism with the 10 sole-supporting surface of said support, at the end of its downward movement.

5. A lip-turning machine comprising a sole support, a plow for raising the lip, an arm pivotally mounted beneath said support 15 and at one side thereof, said arm extending upwardly therefrom, means to oscillate said arm, a holder mounted in said arm at its upper end and projecting at approximately right angles thereto over said support, means 20 to permit horizontal adjustment of said holder over said support, and a hammer carried by said holder at its end and having a

downwardly facing lip-engaging face arranged to be carried over and toward the face of said support as said arm is swung. 25

6. A lip-turning machine having a horizontally disposed sole support, an oscillatory arm having a holder thereon extending over said support, said holder having a vertically disposed socket therein, a hammer reciprocally mounted in said socket, a stop for limiting the downward movement of said hammer, means to vary the vertical position of the hammer while held against said stop, and a spring for normally pressing the hammer against said stop. 30 35

In testimony whereof, I have signed my name to this specification, in the presence of two subscribing witnesses.

EDWIN A. WEBSTER.
